Patented Nov. 9, 1920.

INVENTOR
William C. Cutler

UNITED STATES PATENT OFFICE.

WILLIAM C. CUTLER, OF NORTH GLENDALE, CALIFORNIA.

UNDERREAMER.

1,358,299.

Specification of Letters Patent.

Patented Nov. 9, 1920.

Application filed January 12, 1920. Serial No. 350,759.

To all whom it may concern:

Be it known that I, WILLIAM C. CUTLER, a citizen of the United States, residing at North Glendale, in the county of Los Angeles and State of California, have invented a new and useful Underreamer, of which the following is a specification.

This invention relates to devices for underreaming a well below the casing in the well.

10 One of the objects of this invention is to provide a simple but strong tool.

Another object is to solidly connect the center supporting bar to the body of the device.

15 Another object is to have the reaming members oscillate around a fixed point within the body without having to use a pin for the pivot.

Another object is to facilitate the assembling of the whole device.

Another object is to arrange all removable parts so that they can be assembled and in such assembled condition be disposed into the body just requiring the insertion of a 25 cross pin for operatively interconnecting the assembled parts with the body of the device.

Other objects will appear from the following description and appended claims as well as from the accompanying drawing, in 30 which—

Figure 1 is a longitudinal sectional view through the operating portion of the device.

Fig. 2 is a cross section on line 2—2 of Fig. 1.

35 Similar numbers refer to similar parts throughout the several views.

The body 3 is provided with a concentric bore 4 from the lower end upwardly to a suitable point, and with a cross bore 5. A 40 supporting bar 6 is provided with a collar or head 7, which fits into the bore 4. The cross bore 8 in the head 7 of the supporting bar 6 is designed to come into alignment with the cross bore 5 in the body 3 for the pin 9. 45 By the pin 9, the supporting bar is solidly connected to the body, the head 7 fitting in the bore 4 so as to hold the bar 6 in such a concentric position within the bore 4 of the body 3 as to form a good solid interconnection between the body and the reaming members 10 and 11. The lower end 12 of the supporting bar is flattened to fit between the reaming members, and, near the lower 50 termination of the flat end, provided with two bosses 13 to engage in corresponding recesses of the reaming members. A washer

14 is disposed above the reaming members within the bore 4 of the body to form a smooth surface between the top ends of the reaming members and the spring 15. A 60 locking ring 16 is disposed above the spring 15 resting against the head 7 of the supporting bar 6. The wedge-shaped circular bead or upwardly projecting portion 17 engages in the correspondingly shaped circular 65 groove 18 in the head 7, and, when the pin 9 is in engaging and interlocking position within the bore 5 of the body and the bore 8 of the head, the wedge-shaped bead also engages with the notches 19 in the pin 9 70 thereby locking the pin 9 within the device and interlocking the whole device, as will easily be understood.

In assembling the device, the ring 16 is first disposed on the supporting bar 6 against 75 the head 7, then the spring 15 is disposed on the supporting bar against the ring 16, then the washer is disposed on the supporting bar against the lower end of the spring, and then the reaming members 10 and 11 80 are engaged over the bosses 13 by their recesses. This whole arrangement is so designed that the several parts will stay so interengaged to be pushed into the bore 4 of the body to a point that the pin 9 can 85 be disposed through the cross bores into its correct interlocking position for interlocking the whole device.

When so interlocked, the reaming members are free to oscillate around the bosses 90 13, operated back to their operative position by the action of the spring 15.

The faces 20 of the reaming members touch one another free enough for the oscillating movement of the reaming members. 95 These faces are at practically right angles to the cutting edges 21 of the reaming members. Recesses 22 are provided within the faces 20 to allow the flattened end 12 to come between the reaming members. The smaller recesses 13 are then naturally within the recesses 22 for the bosses on the supporting bar as will easily be understood. The faces 23 are at practically right angles to the central faces 20, taking up the side pressure during the reaming process in a well. The flattened portion 12 of the supporting bar 6 naturally also tends to resist the side pressure of the reaming members during 100 such reaming operations.

110 The solid interconnection of the supporting bar with the body is intended to make

the flattened end 12 with the bosses practically a part of the body so as to produce a direct operative action of the reaming members in relation to the body, that is a direct 5 oscillating movement below and within the body, the point of oscillation always remaining at the same point in expanded as well as collapsed position of the reaming members during the operative actions of the 10 reaming members in relation to the body.

The spring acts during such operative actions of the reaming members on the top end 24 of the counter levers of the reaming members, pressing these levers downwardly 15 and thereby bringing the reaming members, that is the cutting edges of the reaming members, up to the expanded position in which they are illustrated in Fig. 1. The reaming members are thus always automatically 20 pressed to the lower end of the body in expanded operative position.

Having thus described my invention, I claim:

1. In an underreamer, a body having a 25 concentric bore from the lower end inwardly and having a cross bore at a point near the inner termination of the concentric bore, a supporting bar having a head fitting in the concentric bore of the body and having 30 a cross bore through the head adapted to come into alinement with the cross bore in the body for holding the supporting bar solidly engaged with the body concentric to the bore in the body, the lower end of the 35 supporting bar being flattened and having bosses provided on the opposite sides near the lower termination projecting laterally from the supporting bar, reaming members having means to engage with the lower end 40 of the supporting bar for oscillating movement on the supporting bar in relation to the body so as to extend beyond the periphery of the body in operative position adapted for collapsing within the periphery 45 of the body, a spring inserted between the

head of the supporting bar and the top of the reaming members surrounding the supporting bar adapted to press on the top of the reaming members for holding the reaming members in operative position in relation to the body, a pin inserted through the cross bores of the body and supporting bar having notches in its sides, and a locking ring disposed on the supporting bar resting against the head of the supporting bar having corresponding projections to engage with the notches in the pin, the interengaging of the pin and the locking ring adapted to interlock the whole device. 50 55

2. In an underreamer, a supporting bar 60 having a cylindrical head of a larger diameter than the bar itself near one end and having a flattened portion near the opposite end, the flattened portion having bosses formed thereon projecting laterally from the bar, 65 the cylindrical head forming the engaging means of the bar for solidly engaging within a reamer.

3. In an underreamer, a body having a concentric and cylindrical bore, a supporting 70 bar having a cylindrical head of a larger diameter than the bar itself fitting in the bore of the body and having means solidly engaging the bar with the body and having other means forming the stationary pivot 75 points of the body though such solid interconnection between the bar and the body, reaming members swingably engaging with said pivots in operative relation to the body, and a spring inserted into the body above 80 the reaming members adapted to press on the tops of the reaming members for holding the reaming members in operative position.

In testimony that I claim the foregoing as my invention I have signed my name in 85 the presence of two subscribing witnesses.

WILLIAM C. CUTLER.

Witnesses:

HERMAN NELSON,
C. L. MORRISON.
